UNITED STATES PATENT OFFICE

EDWARD W. HAGUE, OF SCRANTON, PENNSYLVANIA

APPARATUS FOR PRODUCING TWO-TONED GLAZED PAPER

Application filed March 26, 1928. Serial No. 264,895.

The present invention relates to manufacture of paper, and more particularly to paper used for wrapping or other purposes wherein a glazed or glossy finish is desired and has 5 for its object to produce a two-toned paper of this character, one color of which constitutes the foundation or background of the paper whereas the other color or tone is used to produce the name, trade-mark or other 10 identifying means for identifying with the particular goods contained in the package with a particular producer, manufacturer or distributor of the goods. A further object of the invention is to produce a paper of this 15 character in which the two toned finish is provided by a single, simple and practical mechanical operation. Other objects and advantages reside in the special construction, combination and arrangement of the various 20 elements forming the invention as more fully hereinafter described and claimed, reference being had to the accompanying drawings forming part hereof, wherein like numerals refer to like parts throughout, and in which:

25 In the drawing:

Figure 1 is a side elevational view of the apparatus employed for carrying out my invention, with parts broken away and shown in section illustrating the manner in which 30 the paper web is treated with the different solutions in the tank provided for the machine,

Figure 2 is a top plan view,

Figure 3 is a sectional view through the 35 belt drive means and drive pulleys for the pressure roll,

Figure 4 is an end elevational view, and

Figure 5 is a transverse sectional view 40 showing one of the pressure rolls in elevation.

The apparatus employed by me in carrying out the invention comprises a supporting frame 5 having a pair of solution tanks 6 and 7 mounted at the upper portion thereof 45 and disclosed at opposite ends of the frame, the tank 6 being of a considerably increased area than the tank 7 and extending longitudinally of the frame throughout the greater portion of the length thereof. The upper 50 portion of the frame is provided with a pair

of spaced parallel longitudinally extending side frame members 8 within each of which is journaled the ends 9 of an impression roller 10, said roller extending transversely of the frame adjacent the end thereof provided with 55 the tank 6 and is arranged with its lower edge immersed in the solution of said tank. The impression roller 10 may be either of the engraved or embossed type and suitable for creating a relatively shallow impression 60 in the texture of one surface of a strip of webbing as the same passes over said roller. Adjacent the end of the frame 5 provided with the impression roller 10 is arranged a supporting bracket 11 upon which is rotatably 65 supported a roll 12 of paper 13 in web form and adapted to be fed over guide rollers 14 at the upper edge of the same and over the impression roller 10. A guide roller 15 is also arranged at the side of the impression 70 roller 10 opposite from the guide rollers 14, the rollers 14 and 15 cooperating to produce a suitable tension upon the web to enable the impression from the impression roller to be produced in the surface of the paper as the 75 same passes thereover. The solution contained in the tank 6 is formed from blanc-fixe aluminum sulphate, blanc-fixe soda ash together with a suitable amount of dye to produce the desired color and it will be apparent that as this solution is applied to the under surface of the web by the impression roller 10 that the outline of the name, trade- 80 mark or other matter engraved or embossed on the impression roller will be placed on the paper as the same passes thereover. From the impression roller 10 the paper passes between a pair of pressure rollers 16, also over a feed roller 17 and between a second pair of pressure rollers 18, one of each of 85 said pressure rollers 16 and 18 as well as the feed roller 17 having a portion thereof immersed in the solution in the tank 6. The pressure rollers 16 and 18 may be of any suitable construction, the present embodiment of 90 the invention illustrating such rollers arranged in pairs in superposed relation as shown at 19 and 20 and disposed parallel with respect to each other and with the upper of said rollers having its end journaled for 95 100

rotation in adjustable bearing brackets 21 provided with springs 22 normally urging the rollers 19 and 20 in contact with each other. The paper web is fed between the rollers 19 and 20 and it will be apparent that as the 5 same passes therebetween any surplus solution will be forced from the web.

The pressure rollers 16 and 18 are operated through an electric motor 23 by means 10 of a chain and sprocket drive connection provided between one of the rollers and the motor, as indicated at 24, the lowermost of each of said pressure rollers being rotatably supported upon a shaft 25 extending outwardly from the frame and the end of which is mounted a pulley wheel 26 connected for operation with each other by means of a drive belt 27. From the pressure roller 18 the web 13 is fed over a feed roller 28 partly 15 submerged in the solution contained in the tank 7 and from which the paper is fed about a guide roller 29 and upwardly to a drying rack 30. The solution contained in the tank 7 is preferably formed of casein, wax and 20 sodium carbonate, dissolved in water in predetermined proportions which constitutes a transparent dye protecting and finishing coating placed upon the surface of the webbing subjected to the dye solution by the feed roller 28, this coating forming the base 25 for producing the glazed finish on the paper, and which glazed finish is created in any suitable and well known manner by feeding the paper through a suitable glazing machine 30 after the same leaves the drying rack 30. It will be apparent from the foregoing description that by first feeding the web over the impression rolls which is also arranged to coat the surface of the paper with the dye 35 solution, it will be apparent that the engraved or embossed surface of the impression roll will cause the name, trade-mark or other matter or design shown on the impression rolls to be either printed or engraved on the web 40 in a lighter or darker shade from the body of the paper, as the case may be, depending upon the particular type of impression rolls, after which the entire surface of the paper is coated with the dye solution by means of 45 the feed roller 17. By reason of the impression first made in the web by the impression roller 10, the coating of dye applied to the paper by the roller 17 will appear heavy and light on the respective parts of the paper and 50 accordingly produce a two-toned finish. In this manner, the name, trade-mark or other design will stand out prominently upon the surface of the paper. It is to be understood that any suitable solution may be prepared 55 to form the dye for initially creating the two-toned color in the paper and in the dye coating or finishing solution, the character of such solution being well known in the art. It is obvious that my invention is sus- 60 ceptible to various changes and modifications 65

in construction without departing from the spirit of the invention or the scope of the appended claim, and I accordingly claim all such forms of the device to which I am entitled.

Having thus described my invention, what I claim as new is:

A paper finishing machine comprising a supporting frame having a pair of tanks mounted thereon adapted to separately contain a dye and a transparent dye protecting and finishing solution, respectively, the latter being suitable for creating a glazed finish upon the paper when subjected to a suitable polishing or glazing process, an engraved impression roller and a smooth feed roller 70 partially submerged in the dye solution with the former disposed in advance of the latter, a pressure roller arranged forwardly and rearwardly of the smooth roller, and a feed 75 roller partly submerged in said dye protecting and finishing solution tank, each of said rollers being adapted to have a paper web fed thereover whereby to initially receive a coating of dye on a portion of one surface 80 from said engraved roller and subsequently to receive a coating of dye on the entire surface from said smooth roller and a coating 85 of the dye protecting and finishing solution from said roller associated with said last 90 named tank.

In testimony whereof I affix my signature.

EDWARD W. HAGUE.
